2,845,204**EXPLOSION-PROOF CONTAINER FOR INFLAMMABLE LIQUIDS**

Malcolm L. Raymond, Johnstown, Pa.

Application March 18, 1957, Serial No. 646,594

3 Claims. (Cl. 222—468)

The present invention relates to portable containers and storage cans as well as stove reservoirs for inflammable liquids, fuels for example; and has reference in particular to a structural adaptation which, functioning as safety means, minimizes accidental deaths and injuries.

It is a matter of common knowledge that repeated yearly accidents and fires are traceable to the fact that vaporous fumes attending volatile liquids mix with air and produce an explosive mixture analogous to that which is exploded in a useful manner in the cylinders of internal combustion engines and the like. An object of the instant endeavor is to provide a container, or alternatively a stove reservoir, in which structural improvements render the same substantially explosion-proof.

In the common storage can when liquid is poured out over a fire, air rushes in at intervals against the outgoing stream of liquid because nature abhors a vacuum. In the case of the stove reservoir, the small openings at the outlet for ingress of air may become clogged by dirt and lint. Air plus flame or spark must enter via the burners to pass up the feed tube. In both instances, the air-vapor combination in the unoccupied space explodes with dire results. The present invention operates as safety-means by providing a separate entrance for air, eliminating the chance of air plus fire entering otherwise.

In carrying out the structural embodiments of the invention under consideration, a construction is provided which lends itself to incorporation in a conventional type fuel can or stove reservoir and this is accomplished with a minimum of expense. In the latter instance merely by changing the reservoir, without detracting from the appearance while at the same time offering a practical source of life-saving and protection to property by making the can, or reservoir as the case may be, renders the same substantially explosion proof. Briefly, one phase of the inventive concept has to do with a substantially U-shaped tube having its bight portion disposed exteriorly of the dome or upper portion of the can or container, one branch thereof depending into the chamber portion of the can and being slotted. The other branch is exteriorly arranged in respect to the can and is fixed thereto and combines with the bight portion in providing a carrying handle. The terminal portion of the exterior branch is laterally directed and provided with a hollow cross member providing a construction which is somewhat like an inverted T, whereby to provide a highly practical hand grip. In addition the U-shaped pipe provides a vent and allows atmospheric air to enter the chamber portion of the can.

Then, too, novelty is predicated on the provision of a buoyant ball or float which has the additional function of a safety ball check valve. This cooperates with the discharge end portion of the pouring spout and effects a safety closure, all in a manner to be hereinafter described.

Other objects, features and advantages will become more readily apparent from the following description and the accompanying sheet of illustrative, but not restrictive, drawings.

2

In the drawing:

Fig. 1 is a perspective view of an "oil can" or an equivalent inflammable fuel container constructed in accordance with the principles of the present invention.

5 Fig. 2 is a view on a slightly enlarged scale which may be said to be a central vertical section and in which all of the essential parts are disclosed.

Fig. 3 is a fragmentary sectional view based on the showing as is made in Fig. 2 and illustrating the manner 10 in which the ball check valve functions under ordinary pouring circumstances.

Fig. 4 is a view which goes a step further than Fig. 3 and shows how the substantially empty can permits the ball to pass through the bore of the spout and lodge 15 itself in the outer end of the spout to serve as a closure.

Fig. 5 is an exaggerated detail section on the plane of the irregular line 5—5 of Fig. 2.

Fig. 6 is a horizontal section on a slightly enlarged scale taken on the horizontal line 6—6 of Fig. 2.

20 Referring now to the drawings the "container," whether it be a stove reservoir or the like, is here conveniently referred to as a portable can and is denoted generally by the numeral 8 and it has a bottom 10, a cylindrical body portion 12 and a dome-like top 14. As seen in Fig. 1 25 the screw cap 16 for the filler neck 18 is of ordinary construction. Also, the top portion is provided with a truncated conical pouring spout 20 which radiates from the can in a customary manner. The outer discharge end 22 is of a prescribed internal diameter to cooperate with the ball check valve 24. Or stated the other way around, the ball is of an outside diameter so that it may serve as a spout closure in the manner seen in Fig. 4. Then too, it will be seen that there is a sector-shaped plate 26 fixed in the intake end portion of the spout and the lower 30 straight edge 28 of this defines an opening 30 which in effect is a restricted entrance to the spout. The outside diameter of the ball is such that it will clear through this opening 30 as shown in phantom lines in Figs. 4 and 5 in a manner to be further described.

40 A substantially U-shaped tubular member is denoted by the numeral 32 and this has a number of functions. The curvate bight portion 34 is exterior of the can and cooperates with the two parallel branches or limbs 36 and 38 in a defining a carrying handle. This makes it possible to dispense with the usual wire bail (not shown). The limb 36 has its upper portion 40 extending through an opening in the dome welded in place and its lower end positioned just above the bottom 10 where it terminates in a manner denoted at 42 in Fig. 2. The entire enclosed 45 portion of the limb 36 is provided with a lengthwise slot 44 which extends from the upper portion or point 46 down to the terminal end 42. This makes it possible to deliver atmospheric air into the entire chamber portion of the can and especially into the upper portion or space 50 48 when the can is filled or substantially filled with the inflammable fuel or liquid 50. There is a spacing block welded or otherwise secured to the body of the can and the block is denoted at 52 and is interposed between the can and the lower portion of the branch 38 which incidentally terminates in the laterally directed portion 54 at about the median vertical portion of the can proper.

55 This laterally directed portion has a cross-head 56 which has its ends open as at 58 and this together with the 60 laterally portion provides a convenient hand-grip for uplifting and tilting the can in the manner shown in Figs. 3 and 4.

65 It will be evident from the disclosure that the U-shaped tube 32 in the particular form revealed and the manner in which it attaches to and cooperates with the can 8 enhances the utility of the can compared to similarly constructed and performing adaptations. Then, too, the

valved spout, as an added safety feature contributes further and consequently a can having these structural improvements is indeed an advance in the storage can and container art. It will be noted that the diameter of the bore of the U-shaped member 32 is greater than the diameter of the discharge opening 22 of the spout. As before stated the branch 36 is slotted the whole length of the part inside to permit the egress of incoming air regardless of the tilt of the can. The T-shaped portion serves as a hand-grip to facilitate handling and pouring. The bight portion serves as a carrying handle. The fact that both ends 58 of the cross-head 56 are open minimizes the likelihood that the user will ever block inflow of air through both ends 58 at the same time.

The valved spout guards against possible inrush of air and fire through the spout as the last of the contained liquid leaves the can. The ball has a diameter slightly more than the outer end of the spout. On completely inverting the can and assuming the contents are completely poured out, the ball will follow along by suction of the escaping liquid and push out the incoming air from behind to pass down the passage of the spout and block the outer end against inrush of air and fire and will also serve to fall back to the bottom of the can when the can is set upright.

In the case of a reservoir for a stove only the air pipe, which need not necessarily be slotted is required to permit free ingress of air as the fuel is used and the level drops. When filling the reservoir (not detailed) the reservoir is inverted back to its natural position, a finger or other closure over the open outer end prevents fluid from rising in the tube as it rises in the reservoir only to follow around the arc and spill out the outer portion when the reservoir is replaced.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An explosion-proof container for inflammable liq-

uids comprising a can having a pouring spout provided with valving means, a substantially U-shaped pipe having a bight portion and a pair of limb portions, one limb portion projecting into the space of the can and having its lower end terminating above the bottom of the can and also having a slot extending approximately from one end to the other end of said one limb portion, the other limb portion being exteriorly disposed and fastened to the can and the bight portion being arched and cooperating with the top of the can and providing a carrying handle.

2. The structure defined in claim 1, and wherein said valving means comprises a ball check valve located normally in the container and floating atop the liquid in the container, said ball check valve being of an outside diameter greater than the diameter of the bore at the discharge end of said spout so that when the ball enters said bore it may be lodged in the discharge end of the spout to effect a closure for the spout, and a segmental plate-like abutment for said ball check valve fixed in the upper portion of the intake end of the spout and cooperating with the spout in defining a restricted passage between itself and a portion of the spout to prevent the ball check valve from entering the bore in the spout under ordinary fuel pouring conditions yet allowing the ball check valve to pass through the restricted passage when the can is substantially empty.

3. An explosion-proof container for inflammable liquids comprising a can having a valved pouring spout, a substantially U-shaped pipe having a bight portion and a pair of limb portions, one limb portion projecting into the space of the can and having its lower end terminating above the bottom of the can and also having a slot extending approximately from one end to the other end of said one limb portion, the other limb portion being exteriorly disposed and fastened to the can and the bight portion being arched and cooperating with the top of the can and providing a carrying handle, and the terminal of the second named limb portion being of T-shape form and having its ends open and providing a hand-grip.
